UNITED STATES PATENT OFFICE.

MAURICE LACHMAN, OF NEW YORK, N. Y., ASSIGNOR, BY MESNE ASSIGNMENTS, TO BETHLEHEM STEEL COMPANY, OF BETHLEHEM, PENNSYLVANIA, A CORPORATION OF PENNSYLVANIA.

METAL WHEEL.

1,400,173.

Specification of Letters Patent. Patented Dec. 13, 1921.

Application filed November 17, 1919. Serial No. 338,421.

To all whom it may concern:

Be it known that I, MAURICE LACHMAN, a citizen of the United States, and a resident of New York, in the county of New York and State of New York, have invented certain new and useful Improvements in Metal Wheels, of which the following is a specification.

My invention relates to the construction 10 and method of manufacturing metal wheels having rim and spokes integral with one another.

The general object of the invention is to provide a wheel constructed from a section 15 or length of flanged metal bar having flanges at both edges, the flanges being utilized as a continuous rim or part of rim while the spokes consist of sub-divisions of the web or body of the bar.

In carrying out my invention I prefer to use a rolled metal shape which, from its cross-section, is known ordinarily as a channel bar, that is to say, a bar having a flange 20 projecting in one direction only from the general plane of the bar although my invention might be carried out by using a bar having flanges projecting in opposite directions from each edge thereof and as indicated by the dotted lines in Fig. 1, thereby 25 making the shape of bar which is known as an I bar.

Briefly stated my invention consists in constructing the wheel from a section or length of flanged bar in such manner that 30 the flanges of both edges shall be embodied in a continuous rim while the spokes integrally connected with such continuous portions may consist of sub-divisions of the web or base made by dividing said base inwardly 35 from points at or near the flanges of both edges toward the center.

A further object of my invention is to so sub-divide the web or base as to afford a reinforcement for the hub structure at the 40 hub ends of the spokes, said reinforcement being integral with the spokes.

When my invention is carried out with this provision the intermediate part of the web between the spoke ends is left with lateral projections which are bent down or up 45 or suitably folded to operate as a reinforcement and as will be more particularly hereinafter shown and described.

A further object of the invention is to produce a wheel of great strength and rigidity.

In the accompanying drawings:

Figure 1 is a cross-section of a channel bar adapted for carrying out my invention.

Fig. 2 shows the same as sub-divided in its web or body into spoke parts and reinforcements according to my invention.

Fig. 3 is a side elevation and partial section of the completed wheel.

Fig. 4 is a transverse section on the line 4-4 Fig. 3, it being understood that the wheel is rotated sufficiently to cause the spokes proper to be seen in edge view.

Fig. 5 illustrates a similar section or portion of the wheel in which the rim is completed by a piece inserted between the edges of the bar.

1 indicates the flanges and 2 the web of the bar. From a line within the flanges the web or body is sub-divided inwardly toward 75 the center to produce two sets of spokes 3, 3'. At an intermediate line between the ends of the spokes each division may be left with lateral projections 4, as shown, although I do not limit myself to the use of such projections and the divisions might extend 80 across from a point at or near one flange to the other in divisions comprising spoke parts only. With the provision of the intermediate part 5 shown said part may constitute in 85 effect a portion of the hub structure and compose, either alone or in conjunction with the parts 4, a reinforcement. As shown the sub-divisions start from points well within the flange, thus leaving a continuous reinforcement beneath the flange which will be 90 of service in strengthening the rim against collapse under the load, the depth of said reinforcement 6 being anything desired consistently with the general objects to be 95 accomplished by my invention.

The bar having been cut as shown, is bent up to bring the two edges thereof into suitable proximity, the bending being on the dotted lines 7 when the divisions are of the 100 particular shape indicated at the center and the lateral projections 4 are also bent or folded up transversely to the plane of the web, thereby forming the reinforcements 4 and practically serving to space the spoke 105 elements apart at their inner ends where

they are joined in the hub. This folding up or bending of the projections is facilitated by cutting the blank along the lines 8, the bend at the connection of the intermediate part 5 being along the line 9. As shown in Fig. 4, the bending up of the two sides of the bar to bring the flanges into proximity is such that the two sets of spokes provided diverge from the general plane of the wheel outwardly from the hub toward the rim, but obviously they might be brought into such proximity as to converge.

The bar having been bent on the line 7, the flanged edges are bent to the circumference of the rim, thereby causing the inner ends of the spoke elements 3, 3' and the intermediate parts 5 from which they spring, to converge and take the proper position for the completed wheel. The construction thus produced may be combined with the usual hub construction, as indicated, the hub barrel being provided with the hub plate 10 on one end and the fastening plate 10' on the other between which the inner ends of the spokes are located and by which, through the use of suitable bolts, the parts are firmly locked together in a hub structure.

The continuous flanges 1 may be bridged by an outer rim 12 secured thereto to form the finished rim or an inverted circumferentially extending flange or channel bar 13 where the flanges depending between the outer ends of the spokes may be employed as indicated in Fig. 5 and suitably secured in position by welding it to the rib 6.

Other modifications in the assemblage and in the relation of the parts obviously may be adopted without departing from my broad invention.

I prefer to use a channel bar simply because in practice it is easier to be produced in the mill than an I bar or bar having a double flange at each edge.

What I claim as my invention is:—

1. A metal wheel formed of a section of flanged metal bar having flanges at both edges, both bent to the form of the rim, while the spokes in two sets consist of sub-divided portions of the base integrally joined at the hub part of the wheel.

2. A metal wheel consisting of a channel bar the edges of which are both bent to the circumference of the wheel while the spoke portion of the wheel consists of two sets of spokes formed of sub-divisions of the base of the channel bar integrally joined at the center portion of the base in the hub structure.

3. A metal wheel consisting of a section of channel bar the web or base of which is sub-divided to form two sets of spokes extending respectively from opposite ends of a hub part comprising a portion of the web or base between said sets, the flanges of said channel bar being bent to constitute the rim.

4. A metal wheel having continuous rim and spokes integral therewith, said rim comprising both edges of a flanged metal bar while the spokes consist of sub-divisions of the web or base sub-divided from both edges inwardly to form two sets of spokes.

5. A metal wheel consisting of a section of channel bar both edges or flanges of which are embodied in the rim as a continuous part thereof while the web or base is subdivided to form two sets of spokes integrally joined by portions of the base having lateral extensions bent up to form a reinforcement for the hub.

6. A metal wheel consisting of a section of channel bar, the web or base of which is sub-divided to form spokes extending from opposite ends of an intermediate part of the web between spoke ends, the two edges or flanges of said channel bar constituting a circumferentially continuous rim.

7. The method of constructing a metal wheel from a section of bar provided with flanges at its edges, consisting in dividing the web or base inwardly from said flanges toward the center into sections adapted to form spokes, bending the base on longitudinal lines to bring the flanges into proximity and then bending said flanges to the circumference of the rim.

8. The method of constructing a metal wheel from a section of channel bar, consisting in sub-dividing the web or the base of the bar to form spokes, bending up said bar to bring the edges of the channel into proximity and then bending said edges to the circumference of the wheel.

9. The method of constructing a metal wheel with spokes and rim integral from a flanged metal bar, consisting in dividing the web or base of the bar inwardly from points near the flanges toward the center into sections adapted to form spokes, bending the bar to bring the flanged edges into proximity, then bending said flanges to the circumference of the rim.

10. The method of constructing a wheel from a section of bar having flanges at both edges, consisting in dividing said bar inwardly from a point within the flanges into divisions adapted to form spokes, bending up the bar to bring the flanges into proximity and then bending said flanges into the circumference of the wheel, thereby bringing the said divisions at their center into the relation required in the hub structure.

11. The method of constructing a metal wheel from a channel bar, consisting in subdividing the base into spokes integrally connected at the center and there provided with lateral projections adapted to form reinforcements of the hub, bending the sub-divisions of the web to bring the sub-divisions into spoke relation to the flanged edges, bending said flanged edges to the circumference.

ference of the rim and folding or bending the lateral extensions into the relation of reinforcements.

12. The method of constructing a metal wheel with rim continuous circumferentially and spokes integral with said rim from a channel bar, consisting in dividing the web or base inwardly from the flanges toward the center, into sections adapted to form 10 spokes, bending the bar on longitudinal lines to bring the edges or flanges into proximity and then bending said flanges to the circumference of the rim.

13. The method of constructing metal wheels from sections or lengths of roller bar 15 provided with flanges at their opposite edges and utilizing said flanges as rim, consisting

in sub-dividing the base or body of the bar between the flanged edges into two sets of spokes integrally connected in an intermediate portion of the base, bending up the divided portions forming the spokes so that they will extend transversely to the plane of the connecting portion, then bending the flanged edges into the circumference of the 25 rim.

Signed at New York, in the county of New York and State of New York this 12th day of November, A. D. 1919.

MAURICE LACHMAN.
